UNITED STATES PATENT OFFICE.

JOHANN STUMPF, OF BERLIN, GERMANY.

DISTRIBUTION-VALVE FOR STEAM-ENGINES.

1,044,828.

Specification of Letters Patent. Patented Nov. 19, 1912.

Application filed October 25, 1910. Serial No. 588,936.

To all whom it may concern:

Be it known that I, JOHANN STUMPF, a subject of the King of Prussia, and a resident of Berlin, Germany, have invented certain new and useful Improvements in Distribution-Valves of Steam-Engines, of which the following is a specification.

This invention relates to improvements in the distribution valves of steam engines especially steam engines of the uni-directional flow type, that is those steam engines in which steam enters the cylinder at one end and exhausts toward the piston either through ports in the piston or through ports controlled by the piston at or near the end of its working stroke.

The object of the present invention is to provide a form of lift valve which will meet the requirements of a distribution valve for steam engines.

The invention is illustrated in one convenient form in the accompanying drawing which is a cross sectional elevation through a valve according to this invention and part 25 of the casing therefor.

A reciprocating rod *d*, operated in any convenient manner has attached to it a two faced or double beat valve *a*, the faces of which are formed on one piece of metal, 30 preferably steel. This valve is provided with an extended boss *f*, guided on a projecting guide *f'*, formed on a detachable part *g'*. The detachable part *g'*, is fixed to the casing *h*, by means of pins *n*, and carries one of 35 the seats *c'*, of the valve. The other seat *b* is formed on the casing *h*, being cast therewith. It will be seen that the detachable part *g'*, extends from the wall of the casing *h*, toward the cast seat *b*, and thereby the 40 seats *b*, and *c'*, are brought more nearly together. In order however, to provide ample area of flow for the steam or other fluid, the part *g'*, is undercut at *p*, relatively to the seat *c'*. With this arrangement the valve 45 seats may be arranged very closely together thereby diminishing the length of the valve and consequently its weight and also diminishing the relative expansion of the parts under varying temperature. This last 50 fact will be readily understood as it is clear that by diminishing the length of the tubular body subjected to the variable heating action, the amount of the expansion will also be diminished.

55 The valve itself is formed of a rigid body part *a'*, which terminates in a rigidly sup-

ported closing face adapted to rest on the seat *c'*, and which closing face is integral with said rigid body. The rigid body part is of substantially truncated conical form having its base resting on the seat *c'*. Projecting from the conical surface above the base and formed integral with the valve there is an annular resilient web *g*. This web or flange is comparatively thin and at its outer edge it carries the second closing face to coact with the seat *b*, on the casing. This resiliently supported face may thus move relatively to the rigid face. The resiliently supported face overhangs the rigid face by 70 an amount *e*. The valve thus has two couples one of which (at *b*) is forced into engagement by the forward pressure of the fluid to be controlled. This valve face is peripherally freely flexible to conform to 75 distortions of its seat resulting from varying temperature conditions while at the same time it is capable, owing to its resiliency, of opening under a slight excess of back pressure such as may occur on the compression 80 stroke in a uni-directional flow engine. The valve is normally held closed by a spring *g*, and the rod *d*, only acts to raise the valve against the pressure of the spring *g*. If there is no pressure outside the valve, 85 the resilient face should just rest on the seat *b*, and of course in such a case there is no bending moment on the cantaliver ring *x-y*, about the points *y*. I have called the resilient annular web a cantaliver ring of 90 the width *x-y*, as it may be conveniently considered as made of an infinite number of radial cantalivers fixed at *y*, and uniformly loaded by the pressure external to the valve. This pressure tends to force the resiliently 95 supported face into engagement with its co-acting seat.

This form of valve can thus accommodate itself to such variations in the relative positions of the seats and faces as occur in practice due to varying pressures and temperatures.

In ordinary screw down stop valves, the available closing pressure is considerable and in double faced valves it may be sufficient to strain the valve to bring both faces into adequate co-action with their seats. In distribution valves, however, the available closing pressure is limited as it would involve the application of too much energy to 105 operate the valve should these valves be held down by excessive pressure. In distribu-

tion valves therefore, it is of the utmost importance to obtain the best possible closure with the minimum amount of power. In the form of valve illustrated, the spring q , 5 acts to hold the valve down with the rigidly co-acting face and seat in effective co-operation. Practically none of this spring pressure is used to hold the resilient valve face to its seat. The spring q , thus does not require that any internal strain be produced in 10 the valve as has been customary in double beat valves with a resiliently co-acting pair of faces and seats as hitherto proposed. For this reason the spring q , need not be 15 heavy and the power necessary to operate the valve is thus reduced.

The closing pressure of the resilient face on its seat b , is obtained by the resultant of the downward pressure on the cantaliver 20 $x-y$, and the upward pressure of the rigid body on the annulus $x-y$ less e . This practically amounts to the pressure on the annulus e , that is on the overhanging annulus. A consideration of the forces acting on the 25 annular web g , and the conditions required in an ideal valve point to the fact that the annulus e , should be $\frac{3}{8}$ ths of the width of the web, that is to say the resilient face should overhang the rigid face by an amount which 30 is three eighths of the width of the resilient web.

In steam engines where the valve system above described is used for controlling admission of the steam to the cylinder, the 35 resilient web g is, at the end of compression, subjected on its upper side to the boiler pressure and on its lower side to the compression pressure of the cylinder. If the compression pressure is excessive, as it is apt to be 40 occasionally in uni-directional flow engines, the web g , will rise and thus relieve compression. The valve a , is of course only partially balanced but as the valve is, during running, opened at the end of compression, 45 the force required to open it is small and is usually only slightly in excess of the resistance of the spring q .

It will also be readily understood by those engaged in this art that the chief point of 50 importance resides in combining all the above features in a valve which is made in one piece of metal as composite valves made of separate parts would be quite useless as distribution valves in steam engines, compressors or the like.

I claim:

1. A valve, for controlling the passage of fluid in a plurality of streams, having two couples of meeting faces, one couple being 55 resilient, urged to closing position by the forward pressure of the fluid to be con-

trolled, and capable, by its resiliency, of opening under a slight excess of backward pressure, independently of the opening of the other couple. 65

2. The combination with rigid valve seats in different planes, of a metallic valve body having a plurality of valve faces integral therewith, in different planes, and controlling the flow of parallel streams, one of said faces being freely flexible peripherally with respect to its normal plane and subjected to fluid pressure to urge it to its seat. 70

3. A double seat valve comprising a reciprocating valve spindle, an apertured valve body connected to said spindle and carrying a rigid annular valve face, and an integral resilient annular flange having a peripheral valve face which is freely flexible with respect to its normal plane. 75

4. A double seat valve comprising a reciprocating valve spindle, an apertured valve member connected to said spindle and carrying a rigid annular valve face and a resilient annular web having a valve face 85 adjacent to its outer periphery overhanging said rigid valve face by an amount substantially three eighths of the width of said resilient web.

5. In combination a valve casing having a 90 valve seat formed thereon, a detachable seat carrying part fixed in said casing, the seat on said detachable part being nearer to the seat in the casing than the part of said casing to which said detachable part is fixed, 95 said detachable part being also undercut relatively to the valve seat thereon, and a double faced valve, the faces of which co-act with the seats in said casing and on said detachable part respectively. 100

6. In combination, a valve casing, having a valve seat formed thereon, a detachable seat-carrying part fixed in said casing the seat on said detachable part being nearer to the seat in the casing than the part of said casing to which said detachable part is fixed, 105 said detachable part being also undercut relatively to the valve seat thereon, a guide piece arranged centrally on said detachable part, a double faced valve, the faces of which 110 co-act with the seats in said casing and said detachable part respectively and a centrally arranged part on said valve fitting to slide on the centrally arranged guide on the detachable part. 115

Signed at Berlin, Germany, this 8 day of October 1910.

JOHANN STUMPF.
